CLAIM

The ornamental design for a printer, as shown and described.

DESCRIPTION

FIG. 1 is a perspective view of a printer showing my new design;

FIG. 2 is a front view thereof;

FIG. 3 is an enlarged front view of a left window portion thereof; and,

FIG. 4 is an enlarged front view of right window portions thereof.

The broken lines in the drawings illustrate portions of the printer which form no part of the claimed design.
